(57) **CLAIM**

The ornamental design for a firearm barricade shooting and training aid, as shown and described.

DESCRIPTION

FIG. 1 is a perspective view of a firearm barricade shooting and training aid, showing my new design with covers omitted from a frame for clarity of illustration;

FIG. 2 is a front elevational view of FIG. 1;

FIG. 3 is a rear elevational view of FIG. 1;

FIG. 4 is a left-side elevational view of FIG. 1;

FIG. 5 is a right-side elevational view of FIG. 1;

FIG. 6 is a top plan view of FIG. 1;

FIG. 7 is a bottom plan view of FIG. 1;

FIG. 8 is a perspective view thereof, illustrated with the covers attached to the frame;

FIG. 9 is a front elevational view of FIG. 8;

FIG. 10 is a rear elevational view of FIG. 8;

FIG. 11 is a left-side elevational view of FIG. 8;

FIG. 12 is a right-side elevational view of FIG. 8;

FIG. 13 is a top plan view of FIG. 8; and,

FIG. 14 is a bottom plan view of FIG. 8.

The evenly broken lines in the drawings depict stitching which form part of the claimed design; the dash-dot broken lines in FIG. 10 depict the boundary of the claim only and form no part of the claimed design.

1 Claim, 12 Drawing Sheets
